PUMP CONTROL SYSTEM FOR SUCTION
DREDGES

David L. Hofer, Berkeley, Calif.

Application May 13, 1947, Serial No. 747,771

7 Claims. (Cl. 103—35)

1

The present invention has for an object the provision of an automatic control system for suction dredges wherein the pump is driven by an electric motor; the control system being operative to maintain constant velocity in the discharge pipe, as is desirable for efficient operation of the dredge. This invention is a modification of the system shown in U. S. Patent No. 2,224,295 of December 10, 1940.

Another object of the invention is to provide a control system, for the purpose described, which is responsive to fluctuation in the speed of the pump drive motor; the system functioning to accelerate this motor when the velocity in the discharge pipe decreases below predetermined normal, and to decelerate the motor when the velocity is above said predetermined normal.

An additional object is to provide a pump control system, as in the preceding paragraphs, for a suction dredge wherein the pump drive motor of the dredge includes an electrically controlled speed regulator in its current supply circuit; said system including a dynamo driven from such motor, the output of the dynamo varying in proportion to the speed of the motor, and circuit means arranged so that the output of the dynamo actuates said speed regulator for the pump drive motor in a manner to control the latter in inverse relation.

A further object of the invention is to retain, in the present embodiment, the safety circuit arrangement of Patent No. 2,224,295 which "locks" the system, against functioning to increase motor speed, when velocity drop is due to plugging in the suction pipe; and to also retain the circuit means which reduces motor speed below normal if the plug is not promptly relieved.

It is also an object to incorporate, in the system of the present embodiment, another circuit arrangement designed to automatically accelerate the pump drive motor when plugging of the discharge pipe occurs whereby to clear said plug; plugging of the discharge pipe being normally evidenced by below normal velocity in the suction pipe rather than by substantial variance in pump drive motor speed, and said other circuit arrangement being responsive to such below normal velocity to cause such acceleration of the pump drive motor.

A further object of the invention is to provide a practical and efficient pump control system for suction dredges, and one which will be exceedingly effective for the purpose for which it is designed.

These objects are accomplished by means of

such structure and relative arrangement of parts as will fully appear by a perusal of the following specification and claims.

The figure of the drawing is a diagrammatic illustration of the system and included circuits.

Referring now more particularly to the characters of reference on the drawings, the numeral 1 indicates the pump of a suction dredge; there being a suction pipe 2 leading to the intake of said pump, and a discharge pipe 3 to which the pump feeds. The pump 1 is driven from a variable speed electric motor 4, through the medium of an endless drive 5.

Current is supplied to the motor 4 by means of a three-phase energizing circuit 6 having a speed regulator 7 interposed therein, which speed regulator may be in the form of a rheostat or the like.

The speed regulator 7 is adjustable to increase or decrease the speed of the motor 4 by means of a connected, reversible control motor 8.

The control motor 8 for the speed regulator 7 is connected to a reversing circuit 9 which is connected to the same source of supply as the energizing circuit 6; there being a reversing relay unit 10 interposed in the reversing circuit 9, for the selective control, in reverse directions of the motor 8. The reversing relay unit includes a speed increasing control circuit, indicated generally at 11, and a speed decreasing control circuit, indicated generally at 12; the circuit 11 including a pair of wires 13 and 14, and the circuit 12 including a pair of wires 15 and 16. The circuits 11 and 12 are automatically and independently energized from a two-wire current supply circuit, including wires 17 and 18, by means of the following automatic circuiting arrangement:

The variable speed electric motor 4 direct drives a D. C. dynamo 19, the output of which is delivered by an output circuit 20 directly to a contacting voltmeter 21 which includes a switch arm 22 and a pair of spaced contacts 23 and 24 between which the switch arm 22 is disposed; said switch arm being normally between said contacts without engaging either. This is the position of the switch arm 22 when the suction dredge is functioning normally, with the variable speed motor 4 turning at normal R. P. M.

When the speed of the motor 4 drops below normal, with the attendant drop in velocity in the discharge pipe 3, there is a consequent drop in the output of the dynamo 19, whereupon the switch arm 22 falls into engagement with the contact 23. When this occurs it closes the speed increasing control circuit 11, which in turn—act-

ing through the reversing relay unit 10—operates the control motor 8 in a direction to cause the speed regulator 7 to step up or accelerate the speed of motor 4. When the motor 4 again reaches its normal R. P. M. the contacting voltmeter 21 opens, breaking the speed increasing control circuit 11.

The speed increasing control circuit 11 comprises the following:

The wire 13 leads from the reversing relay unit 10 to the wire 17 of the two-wire current supply circuit; there being a normally closed switch 25 of an opposed switch relay, indicated generally at 26, interposed in said wire 13. The wire 14 leads from the reversing relay unit 10 to connection with the contact 23 of the contacting voltmeter 21, and the switch arm 22 is connected by a wire 27 with the wire 18 of the two-wire current supply circuit. Through this arrangement, closing of switch arm 22 with contact 23 energizes the speed increasing control circuit 11, with the result previously explained.

As the motor 4 increases in speed beyond normal, with resultant undesirable increase of velocity in the discharge pipe 3, the output of the dynamo 19 similarly increases, being transmitted by the output circuit 20 to the contacting voltmeter 21, which reacts by closing the switch arm 22 with contact 24. When this occurs the speed decreasing control circuit 12 is energized, causing the reversing relay unit 10 to actuate the control motor 8 in a direction such that the speed regulator 7 slows down the motor 4. When the motor returns to normal R. P. M. the contacting voltmeter 21 opens, with switch arm 22 leaving contact 24, whereupon the speed decreasing control circuit 12 similarly opens and becomes negative.

The speed decreasing control circuit 12 is arranged to produce the above result as follows:

The wire 15 leads from the reversing relay unit 10 to wire 17 of the two-wire current supply circuit, while the other wire 16 of the circuit 12 leads from the reversing relay unit 10 to the contact 24; there being a normally closed switch 28 of an opposed switch relay, indicated generally at 29, interposed in said wire 16. It is thus evident that when switch arm 22 closes with contact 24, the control circuit 12 is energized as switch arm 22 is connected by wire 27 with wire 18 of the two-wire current supply circuit.

The purpose of the opposed switch relays 26 and 29 will hereinafter be described; the coil 30 of the opposed switch relay 26 normally being deenergized so that the switch 25 is normally closed, while the opposed switch relay 29 is of a type wherein the coil 31 is normally energized to maintain the switch 28 normally closed.

If a plug occurs in the suction pipe 2 the motor 4 will of course decrease in speed, and unless some safety arrangement were provided, the above described automatic control system would immediately speed up the motor, with possible serious damage to the pump system of the dredge.

To preclude such result the following safety arrangement is provided:

The numeral 32 represents a mercury type manometer including a tube 33 connected to the suction pipe 2 at one end, and having a vertical column portion depending into the mercury at the other end. This vertical column portion of the tube 33 is of dielectric material, and includes a contact 34 at a point some distance above the mercury. Another contact 35 on the body of the manometer is in contact with the mercury therein. The contact 34 is connected to the wire 18 of

the two-wire supply circuit, and said wire 18 has the coil 30 of the opposed switch relay 26 interposed therein. The wire 17 is connected to the contact 35.

When a plug occurs in the suction pipe 2, the mercury rises in the vertical column portion of the tube 33 of the manometer, thus closing a circuit between contacts 34 and 35, and consequently closing an energizing circuit for coil 30. Upon energization of coil 30, switch 25 snaps open, breaking the speed increasing control circuit 11 so that it cannot function to increase the speed of the motor 4 when plugging conditions exist in the suction pipe 2.

If the plugging condition does not promptly relieve, it is further desirable that the speed of motor 4 be then reduced below normal, and this is accomplished as follows:

A normally open, pressure-drop responsive switch 36 is connected by a pipe 37 with the discharge pipe 3, and said switch 36 is arranged so that if plugging conditions in suction pipe 2 continue, with resultant pressure drop in pipe 3, the switch 36 closes. When this occurs the speed-decreasing control circuit 12 is energized so as to reduce the speed of the motor 4. This is accomplished by the following circuiting:

One side of the normally open, pressure-drop responsive switch 36 is connected by a wire 38 which leads to, and connects with, wire 16 of the speed decreasing control circuit 12; the other switch 39 of the opposed switch relay 26 then being closed as the coil 30 remains energized at such time. The switch 39 is open under normal conditions.

The opposite side of the pressure-drop responsive switch is connected by a wire 40 with the wire 27 which leads back to the wire 18 of the two-wire current supply system; thus closing the speed decreasing control circuit 12. Thus, as long as plugging conditions exist in the suction pipe 2 and do not relieve, the described system is operative—automatically—to prevent the circuit 11 from speeding up the motor 4, and thereafter closes the circuit 12 to automatically decrease the speed of the motor 4. When the plug in the suction pipe 2 relieves, the circuit of course returns to normal.

The pump control system, in its present embodiment, includes a further safety circuiting arrangement operative to speed up the motor 4, under working conditions, when the discharge pipe 3 tends to plug, or engages at the discharge end with a bank or the like. The evidence of resisted flow through the discharge pipe 3 is a vacuum drop in the suction pipe 2, but usually the motor 4—under these conditions—continues at substantially the same speed so that the circuits 11 and 12 would otherwise be unaffected. Upon vacuum drop in the suction pipe 2 by reason of flow resistance in the discharge pipe 3, the mercury in the vertical column portion of tube 33, which normally rests at a level between contact 34 and a series of contacts 41 therebelow, falls below said contacts 41. When this occurs the normally energized coil 31 of the opposed switch relay 29 is deenergized, whereupon the switch 28 opens and the opposed switch 42 closes. Upon closing of switch 42, the speed-increasing control circuit 11 is energized, irrespective of the fact that the contacting voltmeter 21 may be open, i. e. switch arm 22 in normal position. With energization of speed-increasing control circuit 11, the motor 4 is speeded up until the

flow resistance in discharge pipe 3 is eliminated, so that the system can return to normal.

The circuit arrangement which makes possible the last described automatic control comprises a wire 43 which leads from a switch blade 44 engageable, selectively, with one of the contacts 41 on the vertical column of the tube 33. At its opposite end the wire 43 leads to one side of the coil 31, while another wire 45 leads from the other side of said coil 31 to the wire 27. Thus, a circuit is normally established between wires 17 and 18, and the coil 31 through the contacts 35 and 41, but when the mercury falls below the contacts 41, the circuit breaks, and coil 31 is de-energized, causing switch 28 to open and switch 29 to close. Switch 29 is interposed in a wire 46 which leads between wire 27 and wire 14. Consequently when the switch 29 closes the speed-increasing control circuit 11 is energized to increase the speed of motor 4.

In summary of the above described pump control system for suction dredges, such system is operative automatically:

1. To increase or decrease the speed of motor 4, as working conditions may require to maintain normal R. P. M. of such motor, and normal velocity in discharge pipe 3.

2. To break the control circuit for (1) above when plugging conditions in the suction pipe occur.

3. To automatically decrease the speed of motor 4 after plugging conditions in suction pipe 2 do not promptly relieve; and

4. To speed up the motor 4, in the event of flow resistance to the discharge pipe 3, so as to re-establish normal velocity of the latter.

The described system provides an efficient and practical means for the automatic control of the pumping system of suction dredges, and further provides safety controls against damage which might otherwise occur under abnormal working conditions.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention as defined by the appended claims.

Having thus described the invention, the following is claimed as new and useful, and upon which Letters Patent are desired:

1. In combination with a suction pump having a suction pipe and a discharge pipe, a variable speed power drive for the pump, instrumentalities arranged to increase or decrease the speed of the power drive in inverse relation and responsive to variation thereof so as to maintain a predetermined normal working speed, means responsive to excess vacuum in the suction pipe above a predetermined normal operative to lock said instrumentalities to an extent to prevent actuation thereof to increase the working speed of the power drive, and other means responsive to continued excess vacuum in the suction pipe operative to effect actuation of said instrumentalities to decrease the working speed of the power drive below its normal, but only after operation of such first named means.

2. In combination with a suction pump having a suction pipe and a discharge pipe, a variable speed power drive for the pump, instrumental-

ties arranged to increase or decrease the speed of the power drive in inverse relation and responsive to variation thereof so as to maintain a predetermined normal working speed, means responsive to excess vacuum in the suction pipe above a predetermined normal operative to lock said instrumentalities to an extent to prevent actuation thereof to increase the working speed of the power drive, other means responsive to continued excess vacuum in the suction pipe operative to effect actuation of said instrumentalities to decrease the working speed of the power drive below its normal, but only after operation of such first named means, and additional means responsive to below normal vacuum in the suction pipe operative to effect actuation of said instrumentalities to increase the working speed of the power drive above normal.

3. In combination with a suction pump having a suction pipe and a discharge pipe, a variable speed power drive for the pump, instrumentalities arranged to increase or decrease the speed of the power drive, means responsive to excess vacuum in the suction pipe above a predetermined normal operative to effect actuation of said instrumentalities to decrease the working speed of the power drive below its normal, but only after operation of such first named means, and additional means responsive to below normal vacuum in the suction pipe operative to effect actuation of said instrumentalities to increase the working speed of the power drive above normal.

4. In combination with a suction pump having a suction pipe and a discharge pipe, a variable speed power drive for the pump, instrumentalities arranged to increase or decrease the speed of the power drive in inverse relation and responsive to variation thereof so as to maintain a predetermined normal working speed, and means responsive to a vacuum in the suction pipe below a predetermined normal operative to effect actuation of said instrumentalities to increase the working speed of the power drive.

5. In combination with a suction pump having a suction pipe and a discharge pipe, a variable speed power drive for the pump, instrumentalities arranged to increase or decrease the speed of the power drive in inverse relation and responsive to variation thereof so as to maintain a predetermined normal working speed, and means responsive to a vacuum in the suction pipe below a predetermined normal, regardless of the then existent normal speed of the power drive, operative actuation of said instrumentalities to increase the working speed of the power drive above said normal.

6. In combination with a suction pump having a suction pipe and a discharge pipe, a variable speed electric motor driving the pump, a speed control circuit for the motor, said circuit including a motor accelerating sub-circuit and a motor decelerating sub-circuit, means responsive to deceleration or acceleration of the motor relative to a predetermined normal working speed operative to effect actuation of the accelerating sub-circuit or decelerating sub-circuit, respectively, and other means responsive to excess vacuum in the suction pipe above a predetermined normal operative to lock said first named means to an extent to prevent the same from actuating the accelerating sub-circuit.

7. In combination with a suction pump having a suction pipe and a discharge pipe, a variable speed electric motor driving the pump, a speed control circuit for the motor, said circuit including a motor accelerating sub-circuit and a motor decelerating sub-circuit, means responsive to deceleration or acceleration of the motor relative to a predetermined normal working speed operative to effect actuation of the accelerating sub-circuit or decelerating sub-circuit, respectively, and other means responsive to excess vacuum in the suction pipe above a predetermined normal operative to lock said first named means to an extent to prevent the same from actuating the accelerating sub-circuit, and further means responsive to continued excess vacuum in the suction pipe

8. In combination with a suction pump having a suction pipe and a discharge pipe, a variable speed electric motor driving the pump, a speed control circuit for the motor, said circuit including a motor accelerating sub-circuit and a motor decelerating sub-circuit, means responsive to deceleration or acceleration of the motor relative to a predetermined normal working speed operative to effect actuation of the accelerating sub-circuit or decelerating sub-circuit, respectively, and other means responsive to excess vacuum in the suction pipe above a predetermined normal operative to lock said first named means to an extent to prevent the same from actuating the accelerating sub-circuit, and further means responsive to continued excess vacuum in the suction pipe

operative to effect actuation of the decelerating sub-circuit by said first named means, but only after operation of said other means.

7. In combination with a suction pipe having a suction pipe and a discharge pipe, a variable speed electric motor driving the pump, a speed control circuit for the motor, said circuit including a motor accelerating sub-circuit and a motor decelerating sub-circuit, means responsive to deceleration or acceleration of the motor relative to a predetermined normal working speed operative to effect actuation of the accelerating sub-circuit or decelerating sub-circuit, respectively, other means responsive to excess vacuum in the suction pipe above a predetermined normal operative to lock said first named means to an extent to prevent the same from actuating the accelerating sub-circuit, further means responsive to continued excess vacuum in the suction pipe operative to effect actuation of the decelerating sub-circuit 20

by said first named means, but only after operation of said other means, and additional means responsive to below normal vacuum in the suction pipe, regardless of the then existent normal speed of the motor, operative to effect actuation of the accelerating sub-circuit by said first named means.
